UNITED STATES PATENT OFFICE.

HERMAN KROHN, OF EASTON, PENNSYLVANIA.

DESIGN FOR A COMBINED INKSTAND, PENRACK, DESK LAMP, AND ELECTRIC FAN.

Application filed November 19, 1928. Serial No. 28,948. Term of patent 7 years.

To all whom it may concern:

Be it known that I, HERMAN KROHN, a citizen of the United States, residing at Easton, in the county of Northampton and State of Pennsylvania, have invented a new, original, and ornamental Design for a Combined Inkstand, Penrack, Desk Lamp, and Electric Fan, of which the following is a specification, reference being had to the accompanying drawing, forming part thereof.

Figure 1 is a side elevation of a combined ink stand, pen rack desk lamp and electric fan, showing my new design and

Fig. 2 is a front view thereof.

I claim:

The ornamental design for a combined ink stand, pen rack, desk lamp and electric fan, as shown.

HERMAN KROHN.
